MARIUS MATHIESEN, OF CHICAGO, ILLINOIS, ASSIGNOR, BY MESNE ASSIGNMENTS, TO
WILLIAM J. SANDBERG.

PORTABLE AERIAL.

Continuation of application Serial No. 754,123, filed December 5, 1924. This application filed February 24, 1925. Serial No. 11,213.

My invention relates to improvements in portable aerials for use in radio work and has special reference to improvements in collapsible portable loop aerials.

5 The object of my invention is to provide a loop aerial which shall be readily collapsible into a relatively small compact compass for transportation, and which shall be capable of being readily and quickly extended for 10 use.

The device of my invention comprises an extensible mast combined with arms hinged to the mast, and insulators secured to the ends of the mast and arms upon which the 15 aerial wire is wound in loop form. One pair of the arms is hinged to a member which is mounted to slide on the mast in the collapsing and extending operations, and the arrangement is such that the final 20 positioning of this pair of arms in extended relation serves to tension the loop wires and hold them in proper and orderly extended relation.

Further features of importance will be 25 come clear from the following description taken in conjunction with the accompanying drawings forming part of this specification and in which:

Figure 1, is a perspective view of the device as it appears extended for use;

Figure 2, is an elevational view showing the device in collapsed condition;

Figure 3, is an enlarged, fragmentary view illustrating the telescopic connection 35 of the two parts of the mast or central member and the hinging of one pair of arms thereto; and

Figure 4, is a fragmentary, vertical, sectional view on the line 4-4 of Figure 3.

40 In the form of my improved device, as illustrated in the drawings, 1 illustrates a base upon which the loop device proper is adapted to be rotatably mounted to be swung around on a vertical axis for the purpose of 45 obtaining the best results. The device proper comprises a central vertical mast 2, which consists in the form shown of a lower tubular part 3 and an upper part 4, the lower part of which is adapted to slide up 50 and down in the tubular part 3. These two parts of the mast are so related that they cannot rotate in relation to each other, preferably by both being square in cross-section and the part 4 fitting within the tubular

part. The device proper is rotatably mounted on the base by means of a vertical bearing pin or stud 5 fixed to the base and standing therefrom, and the lower end of the tubular part of the mast being filled with a plug 6 and provided with a vertical opening substantially fitting the pin 5. The upper member 4 of the mast is slidable down into the tubular part 3 to shorten the mast, as best shown in Figure 2, when the device is collapsed.

As the space available for such devices is often more or less limited horizontally, while being ample vertically, a particular feature of improved collapsible loop is that I am enabled to make a loop which is elongated vertically and reduced horizontally while yet carrying an ample length of wire. The construction which enables me to attain this improved form of loop includes the provision of two pairs of horizontal arms 7-8 and 9-10, respectively, spread apart vertically of the mast. The lower pair of arms, viz, 7-8, are hinged to the sides of the upper end of the tubular part 2 of the mast, as shown at 11. The arms are secured above 80 the hinges so that they can swing down parallel with the part 3 of the mast when they are collapsed. The inner ends of these arms 7 and 8 are arranged to contact squarely with the sides of the tube 3, when in 85 extended position, and they are thereby prevented from being swung above a horizontal position. The upper pair of arms 9-10 are hinged to a short tubular member 12 arranged to slide up and down on the upper 90 part 4 of the mast, the extended position being such that the two arms 9 and 10 are arranged horizontally and parallel with the lower arms 7 and 8.

At the outer ends of the arms and at the 95 upper and lower ends of the mast, I provide laterally extending insulators or wire supports 13, each comprising a fixed cross-member 14 and a removable cap member 15. The members 13 may be provided with 100 spaced apart shallow notches 16 for receiving the turns of the aerial wire 17, and then when the cap members 15 are secured in position the wires are tightly clamped in position on the ends of the several arms.

For holding the mast 2 in extended position, I provide a simple means of latching the two members 3 and 4 together. As

shown, this means consists of a spring pressed plug or pin 18 mounted in a pocket 19 in the lower end of the upper part 4 of the mast and adapted to project through an opening 20 provided in one side near the upper end of the tubular part 3 of the mast. I provide a spring 21 in the pocket 19 to press the pin 18 outwardly and I taper the outer end of the pin to facilitate the latching and unlatching of the two parts of the mast. The pin is provided with an enlarged base to prevent its escape through the hole 20.

The sliding member 12 is adapted to be similarly latched to the upper part 4 of the mast, being provided with an opening 22 to receive a spring pressed latch pin 23.

During the process of winding the several turns of the wire 17 on the arms, the mast is preferably fully extended, and I preferably secure the sliding support 12 of the arms 9 and 10 in a position higher than the fully extended position, and with the arms 9 and 10 extending in a slightly upwardly inclined relation, as indicated in dotted lines in Figure 1, so that when the device is completed and the support 12 is pushed down to its fully extended position the several turns of the wire 17 will be tensioned by the spreading apart of the free ends of the arms 9 and 10 in the extending operation. The free end portions 24 of the wire 17 are preferably secured to the lower cross arm 13 and can be connected in any suitable manner with the devices for which the aerial is designed to be used.

It is to be noted that in collapsing the device the sliding member 12 can first be unlatched and slid up the upper part 4 of the mast, thus relieving the tension of the loop wire, and the two arms 9 and 10 swinging in against the mast, then the two parts of the mast can be unlatched and the upper part 4 telescoped down into the lower part 3, and at the same time the two lower arms 7 and 8 can be swung down and in against the lower part 3 of the mast, thus bringing the several parts into compact collapsed relation.

As many modifications of my invention will readily suggest themselves to one skilled in the art, I do not limit or confine my invention to the specific constructions and arrangements of parts herein shown and described.

This application is a continuation of my copending application entitled *Folding loop aerial*, filed December 5, 1924, Serial Number 754,123.

I claim:

1. A collapsible loop aerial comprising a mast adapted to be positioned vertically and comprising a pair of telescopic members, a pair of cross arms hinged on one of said

members, an arm support member slideable along the other of said telescopic members, a pair of cross arms hinged to said slideable member and means for securing said telescopic members and said arms in extended position.

2. A collapsible loop aerial comprising a two part mast, one part being a tube and the other part a rigid member telescopically mounted in the tube, a pair of laterally extensible arms hinged to the inner end of the tubular member, an arm support slideable on the rigid member, and a second pair of arms hinged to said slideable arm support.

3. A folding loop aerial comprising a base, to which is swiveled a vertically extending tube, horizontally extended arms hinged to the upper end of said tube, a vertical extension slideable within said tube, a collar slideable along said vertical extension and cross arms hinged to said collar.

4. A folding loop aerial comprising a base, a mast extending vertically therefrom, said mast comprising a pair of telescopic members, a pair of cross arms hinged on one of said members, and a collar slideable along the remaining one of said members, a pair of cross arms hinged to said collar, and means for latching said members and arms in extended position, and insulators carried at the ends of said members and arms, suitable for retaining against shifting an antenna wire looped around the same.

5. In a collapsible loop aerial, a two part mast adapted to be extended, oppositely disposed arms hinged to one part of the mast, a member slideable along the other part of the mast, a pair of oppositely disposed arms hinged at their inner ends to said member, cross arms at the ends of the mast and the several arms, an aerial wire wound on the cross arms, the sliding member being adapted to extend and collapse the arms hinged thereto, and latch means for retaining the sliding member in arm extending position.

6. In a collapsible loop aerial, a frame having a mast comprising two telescopically movable parts, latch means for holding said parts in their extended positions, arms for the frame adapted to be extended laterally, a member slidably mounted on one of the mast parts to which a pair of arms are hingedly mounted, an aerial wire wound around the extremities of the arms and mast when frame is not fully extended, the sliding member carrying the arms hinged thereto being movable along the mast to act, in conjunction with the arms hinged thereto, as a toggle lever to extend the frame and tension the turns of aerial wire.

In testimony whereof, I have hereunto set my hand, this 18th day of February, 1925.

MARIUS MATHIESEN.
